UNITED STATES PATENT OFFICE.

RALPH M. JACKSON, OF LA HABRA, CALIFORNIA.

ILLUMINATING DEVICE AND ADJUSTABLE SUPPORTING MEANS THEREFOR.

No. 910,066.

Specification of Letters Patent.

Patented Jan. 19, 1909.

Application filed October 16, 1907. Serial No. 397,733.

To all whom it may concern:

Be it known that I, RALPH M. JACKSON, a citizen of the United States, residing at La Habra, in the county of Orange and State 5 of California, have invented a new and useful Illuminating Device and Adjustable Supporting Means Therefor, of which the following is a specification.

An object of this invention is to provide 10 an illuminating device having adjustable supporting means therefor, said means being adapted to rest on top of an article of furniture, more particularly a piano or like musical instrument, and to support the 15 illuminator at various heights and in different lateral positions for the purpose of throwing a satisfactory light upon the music sheet.

A further object of the invention is to 20 provide means for supporting a piano light in the proper position for throwing light on the music whether said supporting means is placed on an upright piano of the taller sort or on a low flat-topped piano.

25 By furnishing supporting means for the fuel supply tank at one side thereof, and slightly offsetting said means from the portable base, and extending the fuel-supply and lamp-supporting pipe from the other side of 30 said reservoir, a construction is provided which makes it possible to adjust the lamp to positions below the level of the base, and at the same time maintain the lamp and tank on the same level to cause an even flow 35 of oil to the lamp.

Another object is to provide, in combination with the supporting means, means for supplying an even flow of oil to the bowl of the lamp when an oil lamp is used for the 40 illuminator.

A still further object is to provide a device of the character stated composed of comparatively light parts so connected together as to be readily separated and packed 45 in convenient form for sending through the mails.

Other objects and advantages may hereinafter appear.

50 Referring to the accompanying drawings which illustrate the invention, Figure 1 is a side elevation of the invention embodied in a lamp and supporting means therefor resting upon an upright piano in position for use. Fig. 2 is a perspective view showing the parts of the invention slightly separated from each other, but arranged in ap-

proximately the position they occupy when assembled for use.

The invention consists in the various parts, in the combinations and constructions set forth in the general description, and particularly defined in the claims.

It is to be understood that the invention is not limited to the use of the particular kind of illuminator illustrated.

60 The invention in the embodiment thereof illustrated in the drawings, comprises the base 1 provided with a holder 2 for adjustably supporting the other parts of the device. The supporting means proper in the 70 preferred form of the invention, comprise a vertical rod 3 having a yoke 11 attached to one end thereof, said yoke having horizontal arms 12.

65 The illuminating device may comprise the 75 tank 4, fuel supply-pipe 5 and the lamp 6 supplied with fuel from the tank through said pipe, or other illuminating means may be provided for being mounted detachably upon the arms 12 of the yoke.

70 The fuel supply may consist of a tank 4, and may be connected by fuel feeding arm 5 with the illuminator 6.

75 In the present embodiment of the invention, a weighted base 1 is provided with a 80 short extension 7 which carries an upright arm 8 having an open-ended bore 9 extending therethrough so that stem 3 may be inserted into the bore from either end thereof, and adjustably supported therein by set- 90 screw 10 which forms part of the holding means. Rod 3 is reversibly mounted in the socket of arm 8 and is provided at its outer end with attaching means consisting of a yoke 11 having arms 12, tank 4 being remov- 95 ably mounted on said arms by means of keeper or loop 13 at each end thereof.

14 is a removable cap for supplying oil or other fuel to tank 4.

15 is a regulating wick, preferably a round 100 wick which practically fills the inside of tube 5 and extends from end to end thereof to prevent an oversupply of the oil from rushing into the bowl 16 of the lamp if the latter is accidentally tipped below the level 105 of tank 4.

17 designates the usual lamp wick, 18 the ordinary burner and 19 the chimney.

20 is a broad reflector and shade adapted to shade the eyes of the musicians and to 110 throw the light upon the sheet of music 21 supported by piano 22. Reflector 20 may be

removably mounted in a socket 23, so that the same may be readily removed for cleaning or when the apparatus is to be packed for shipment.

5 A strengthening web 24 may be soldered to tank 4 and pipe 5 to fasten said parts more securely together.

25 designates rivet-shaped pieces of rubber or like material cemented into holes or 10 otherwise fastened to base 1 to prevent said base from marring furniture.

Base 1 is preferably made of metal and is sufficiently heavy to at all times more than counterbalance the parts supported thereby.

15 The elongated tank 4, when mounted on the reversible support in either position of said support extends in such a direction that the length of the tank is substantially parallel with the side of the base next thereto. 20 This construction lessens liability of the base being overbalanced by the tank, because the weight of the tank is placed nearly in vertical alinement with said base.

In an illuminating apparatus constructed 25 according to the principles of this invention a light may be adjustably supported either above or below the level of the support upon which the apparatus as a whole rests and said light may also be swung to different 30 points of lateral adjustment.

I am aware that prior to my newly invented means for supporting an illuminator, lighting means have been provided with supports mounted on weighted bases and that 35 there have also been provided various means for supporting and vertically adjusting a lamp on a fixed support; but so far as I am aware, no such portable base has hitherto been combined with a longitudinally adjustable vertical lamp-carrying rod mounted on 40 said base or on an extension close to the weighted portion thereof. In order to make a portable base available as a means for supporting illuminating apparatus, it is necessary that the weight of said apparatus be 45 thrown close to the center of gravity of said base. The fuel supply tank 4 weighs far more than the lamp 6, and said tank is therefore, as illustrated in the drawings, thrown 50 very close to vertical alinement with the edge of base 1. Otherwise, it would be impossible to extend the lamp 6 a sufficient distance from the top of the piano to throw the light squarely against the surface of the music- 55 sheet 21 without overbalancing the base.

It is to be understood that although the drawings illustrate what is at present deemed the most desirable embodiment of the invention, various alterations within the skill of 60 the workman may be made in the construction illustrated and described without departing from the scope of the invention.

I claim:

1. In combination, holding means, means 65 for mounting said holding means on an

article of furniture, a support mounted on said holding means, said support including a yoke having horizontally extending arms, and illuminating means detachably mounted on said arms, the ends of said support being 70 interchangeable to bring said yoke above or below said holding means.

2. In combination, holding means, means for mounting said holding means on an article of furniture, a support mounted on 75 said holding means, said support including horizontally extending arms, a fuel supply tank having keepers adapted to removably support said tank on said arms, a conduit extending from said tank, and an illuminator supported by and supplied through said conduit.

3. In combination, holding means, means for mounting said holding means on an article of furniture, a support mounted on 85 said holding means and vertically adjustable with relation thereto, said support including a yoke having horizontally extending arms, a fuel supply tank having a keeper at each end thereof adapted to engage an arm of 90 said yoke to removably support said tank, a horizontal conduit extending from said tank, and an illuminator supported by and supplied with fuel through said conduit.

4. In combination, a portable base consisting of a counterbalancing weight having an extension projecting horizontally therefrom, a vertical arm carried by said extension, said arm having an open-ended bore extending therethrough, a rod adapted to slidably and 100 revolvably engage said bore, a set-screw carried by said arm to maintain said rod in fixed position therein, a horizontal yoke mounted on one end of said rod, a pair of arms projecting laterally from said yoke, an 105 elongated tank, a keeper carried by said tank at each end thereof, said keepers adapted to removably engage said arms of the yoke, a conduit projecting from said tank, and an illuminator carried by and supplied with 110 fuel through said conduit.

5. The combination, with a portable weighted base, of holding means on said base, approximately in line with a side edge thereof, a slideable vertical rod adjustably mounted on said holding means, an attaching yoke on said rod, and illuminating means provided with keepers adapted to removably engage said yoke.

6. The combination, with a portable 120 weighted base, of holding means on said base, a slideable vertical rod adjustably mounted on said holding means, a yoke on said rod, a fuel tank, keepers at the ends of said tank adapted to engage the arms of said yoke, and a burner supported by and supplied with fuel from said tank.

7. In combination, a base consisting of a counterbalancing weight, a vertical arm extending upwardly from said base at one edge 130

- thereof, said arm having an open-ended bore extending longitudinally therethrough, a rod slidably engaging said bore, means to adjustably maintain said rod in said bore, a 5 fuel tank, means supporting said tank at the upper end of said rod, said rod extending approximately in vertical alinement with one side of said tank, a fuel supply pipe projecting from the side of said tank opposite 10 said rod, and an illuminator carried by the outer end of said pipe and supplied with fuel therethrough.
8. In combination, a counterbalancing weight comprising a base adapted to sit on 15 an article of furniture, holding means carried by said base and offset from one edge thereof, a fuel supply tank mounted on said holding means, a supply pipe projecting from the side of said tank farthest from the 20 center of gravity of said base, and an illuminator supported by the outer end of said pipe and supplied with fuel therethrough.
9. In combination, a portable base, a fuel-supply tank, a lamp spaced horizontally 25 away from said tank, a fuel-supply pipe ex-
- tending from one side of said tank to said lamp, and means supported by said base and adjustable to points below the level thereof for supporting said tank, said means being located in operative position at the side of 30 said tank opposite said lamp.
10. In combination, a portable weighted base, a fuel tank, an illuminator, a laterally extending pipe to supply said illuminator with fuel from said tank, and means offset 35 slightly beyond vertical alinement with one side of said base for supporting said tank, said means being adapted for adjustment to bring the lamp to the side of the tank opposite said base. 40
- In testimony whereof I have hereunto signed my name in the presence of two subscribing witnesses at Los Angeles, in the county of Los Angeles and State of California, this ninth day of October, 1907.

RALPH M. JACKSON.
